UNITED STATES PATENT OFFICE.

JOHN A. SHEA, OF WILKES-BARRE, PENNSYLVANIA.

GARMENT-HANGER.

1,115,116.

Specification of Letters Patent. Patented Oct. 27, 1914.

Original application filed July 10, 1912, Serial No. 708,716. Divided and this application filed December 28, 1912. Serial No. 739,131.

To all whom it may concern:

Be it known that I, JOHN A. SHEA, citizen of the United States, residing at Wilkes-Barre, in the county of Luzerne and State 5 of Pennsylvania, have invented certain new and useful Improvements in Garment-Hangers, of which the following is a specification.

This invention relates to garment hangers and more particularly to that class or such hangers as are made use of in clothing stores for the purpose of displaying coats and other articles of wearing apparel, and which include an extensible coat-hanger 15 support.

It is the primary aim of the present invention to provide in an extensible hanger of this class, means for automatically extending the same upon opening of the door 20 of a cabinet or case within which the hanger is arranged.

In the instance of the present invention the member to be extended is in the nature of a hanger-rod, and this rod is provided at 25 its forward end with a suction cup device which coöperates with the inner face of the door in such manner that when the door is moved to open position, the adherence of the cup to the face of the door will result 30 in the hanger rod being pulled out to extended position.

This application is a division of my co-pending application Serial No. 708,716, filed July 10, 1912, in which the construction 35 of the hanger in connection with which the device of the present invention is employed, is fully described and shown.

In the accompanying drawings: Figure 1 is a perspective view of so much of the 40 hanger as is necessary to illustrate the present invention and its application. Fig. 2 is a plan view illustrating the manner in which the suction cup at the end of the hanger rod is arranged to coöperate with 45 the door of the case or cabinet within which the hanger is arranged. Fig. 3 is a horizontal sectional view illustrating the suction device in detail.

Corresponding and like parts are referred 50 to in the following description and indicated in all the views of the drawing by the same reference characters.

As stated, the hanger proper forms the

subject-matter of my co-pending application and consequently will only be briefly described herein. 55

The hanger includes a guide 1 which is mounted upon the under side of the top of the cabinet A within which the hanger is arranged, the door of the cabinet being indicated at B. One extensible member of the hanger is in the nature of a slide 2 mounted in a rod 3 so that it may be supported within the case A or may be pulled out to extend beyond the front of the said 60 case. This slide includes a hanger rod 3 with which may be engaged the hooks of the garment hanger in the manner shown in Fig. 1.

A bracket 4 extends laterally and upwardly from the rod 3 and is provided with a sleeve 5 in which is slidably fitted a hanger rod 6, it being understood that this hanger rod being slidable with the sleeve may be positioned to extend beyond the forward 75 end of the slide 2 or to extend beside the said slide. This hanger rod 6 is auxiliary to the rod 3 and serves as a suspension means for the garment hangers which have been disengaged from the rod 3 for the purpose 80 of displaying the garments hung therefrom. The forward movement of the hanger rod 6 is limited by a stop or head 7 located at its rear end, this head being designed to abut 85 against the rear end of the sleeve 5.

The means above mentioned as provided for the purpose of automatically sliding the rod 6 forwardly when the door is moved to open position, consists of a suction cup 8 which is secured at the forward end of the 90 rod 6 by means of a screw 9, the head of which is embedded in the neck of the cup, the concaved side of the cup being presented forwardly.

By referring to Fig. 2 of the drawing it 95 will be apparent that when the door is closed its inner face will strike against the cup 8, whereupon the cup will adhere to the door so that when the door is swung to open position a forward pull will be exerted upon 100 the rod thereby sliding the same forwardly to about the position shown in Figs. 1 and 2 of the drawing. The cup 2, will of course, disengage from the door when the door has been partly opened.

By referring to Fig. 3 of the drawing it

will be noted that the forward end portion of the rod 6 is threaded, as indicated at 10 and a circular head 11 is formed axially with an opening 12, the wall of which is 5 threaded, and this head is adjustably fitted onto the end of the rod 6 and serves as an abutment to limit the sliding movement of the rod 6 by striking against the forward end of the sleeve in which this rod is slidably mounted. It will be apparent that by 10 adjusting this head 11 upon the rod 6, the forward end of the rod, or more specifically the cup 8 may be positioned a greater or less distance in advance of the forward end of the slide 2 when the rod 6 is slid inwardly 15 until the head 11 abuts against the sleeve 5. In this manner, the cup may be adjusted with relation to the face of the door when the latter is in closed position so as to insure of its proper engagement with the door. This head 11 also serves as a means to prevent the garment hangers upon the rod 6 sliding past the forward end of the said rod while the garments are being inspected.

25 In order that the head 11 will not be likely to mar any portion of the case which comes in contact therewith, for example, when the device is applied to or employed in connection with a revolving hanger the head 11 is formed peripherally with a 30 groove 13 in which is fitted a soft rubber ring 14.

Having thus described the invention what is claimed as new is:—

35 1. In a device of the class described, the combination with a case having a movable door, and an extensible support mounted within the case, of a bracket mounted upon the support, a hanger rod slidably mounted 40 in the bracket, and means carried by the hanger rod and coöperating with the door for retracting the said hanger rod when the door is moved to open position, said means comprising a suction cup carried by the rod

and arranged to coöperate with the face of 45 the door.

2. In a device of the class described, the combination with a case having a door, and a hanger rod mounted within the case and relatively fixed, of a hanger rod slidably mounted upon the first mentioned rod, and means carried by the last mentioned hanger rod and arranged to coöperate with the door to slide the said last mentioned rod forwardly when the door is moved to open position, the said means being free from permanent and fixed connection with the door. 55

3. In a device of the class described, the combination with a case having a door, and a relatively fixed hanger rod mounted within the case, of a bracket mounted upon the hanger rod, an auxiliary hanger rod slidably mounted in the bracket, an adjustable abutment upon the auxiliary hanger rod arranged to coöperate with the bracket to 60 limit the inward sliding movement of the rod, and suction means at the forward end of the auxiliary rod arranged to coöperate with the inner face of the door whereby the auxiliary rod will be slid forwardly when 65 the door is moved to open position.

4. In a device of the class described, the combination with a relatively fixed support, of a bracket mounted thereon, a hanger rod slidably mounted in the bracket, the said 70 rod at one end being threaded, a head adjustably threaded upon the said end of the rod and constituting an abutment for coöperating with the said bracket to limit the inward sliding movement of the rod, and a 75 suction cup arranged at the forward end of the said rod.

In testimony whereof I affix my signature in presence of two witnesses.

JOHN A. SHEA. [L.S.]
